APPARATUS FOR FILLING CONTAINERS
Uwe Naecker, Hamburg-Bergedorf, Germany, assignor to
Firma Ortmann & Herbst, Hamburg, Germany
Filed July 19, 1962, Ser. No. 211,053
Claims priority, application Germany July 20, 1961
12 Claims. (Cl. 141—57)

The present invention relates to an apparatus for filling containers with liquid under pressure, and more particularly to an apparatus which is used in an automatic filling machine for filling bottles with a liquid containing a gas.

In known machines of this type, an inlet tube and an outlet tube for gas are inserted into the container. When the filling of the container is completed, the air or carbonic acid is under pressure in the outlet tube, and when the space in the container above the liquid is vented, the air in the outlet tube expands into the liquid and causes foaming of the same. In order to prevent that the foaming liquid is discharged from the bottle or container it is necessary to fill the liquid in very cold condition, and to very gradually relieve the pressure in the filled container, which results in comparatively slow and uneconomical filling operations.

It is one object of the invention to overcome the disadvantages of known filling apparatus, and to provide an apparatus by which liquid under pressure can be filled into containers without causing foaming or turbulence of the liquid when the filled container is relieved from pressure and separated from the filling apparatus.

Another object of the invention is to release air and gas compressed in the outlet tube into the container at a level above the level of the liquid in the filled container.

Another object of the invention is to provide a simple and reliably operating filling apparatus constructed of a few parts.

With these objects in view, one embodiment of the invention comprises a tube which is inserted into a container or bottle for receiving the discharged air when the bottle is being filled, valve means forming a valve chamber having a lower inlet located at the desired level of a liquid in the container, and a higher outlet, a removable valve element, such as a ball heavier than the liquid and being movable between positions closing the inlet and the tube, respectively, and an open position, and a movable valve member having a normal position for blocking passage of air through the outlet and an actuated position permitting passage of air through the outlet.

During a filling operation, the liquid enters the container while the air and gas in the container escapes through the inserted tube, while moving the ball to the position in which the inlet of the valve chamber, and the tube are open. When the liquid raises to the desired level, the escaping gas produces a greater pressure and moves the ball to a position closing the outlet tube so that gas and air can no longer escape, and the flow of liquid into the container is terminated. Thereupon, the device is raised, and the supply of pressure liquid separated from the container so that the ball drops to a position closing the inlet to the valve chamber. When the space in the container above the liquid is now vented and connected to atmospheric pressure, the pressure in the valve chamber is greater than in the container, and the movable valve member responds to this increased pressure to permit passage of air through the outlet into the gas and air filled space in the container.

In this manner, liquid having entered the valve chamber and air and gas are blown into the air space of the container where no turbulence is caused, whereas in accordance with the construction of the prior art, the gas, air and liquid were blown out at the level of the liquid and caused turbulence and foaming of the liquid.

2

In accordance with one embodiment of the invention the valve member is tubular and spring loaded so that the pressure in the valve chamber must overcome the spring pressure which normally holds the tubular valve member in a position in which gas and air cannot pass out of the outlet in the upper part of the tubular valve member.

In another embodiment of the invention, the valve member is a ring slidable on the outlet tube and normally closing the higher outlet of the valve chamber. When the pressure in the valve chamber is increased and higher than the pressure in the vented container, it moves valve ring to an actuated position opening the higher outlet of the valve chamber.

In a third embodiment of the invention, the valve chamber is formed by a tubular valve member which has a lower inlet, and a plurality of openings arranged in a circle and forming the higher outlet of the valve chamber. A valve ring is again provided which normally rests on the openings forming the outlet and closes the same. When the pressure in the valve chamber is increased, the valve ring is raised, and the air, gas and liquid having entered the valve chamber can escape through the higher outlet into the space in the container above the liquid level.

The novel features which are considered as characteristic for the invention are set forth in particular in the appended claims. The invention itself, however, both as to its construction and its method of operation together with additional objects and advantages thereof, will be best understood from the following description of specific embodiments when read in connection with the accompanying drawings, in which:

FIGS. 1, 2 and 3 are corresponding fragmentary sectional views illustrating three operational positions of a first embodiment of the invention;

FIGS. 4, 5 and 6 are three corresponding fragmentary sectional views illustrating three operational positions of a second embodiment of the invention;

FIG. 7 is a cross sectional view taken on line 7—7 in FIG. 6;

FIGS. 8, 9, and 10 are corresponding fragmentary sectional views illustrating three operational positions of a third embodiment of the invention; and

FIG. 11 is a cross sectional view taken on line 11—11 in FIG. 9.

Referring now to the drawings, and more particularly to FIGS. 1 to 3, a filling vessel 2 has a bottom 1 with a sealing ring 6 surrounding an inlet passage 3. A container 5 is pressed with the edge of its neck against the sealing ring 6 so that liquid under pressure can flow out of the filling vessel 2 through passage 3 into the interior of the container or bottle 5. A venting conduit 3a communicates with the inlet passage 3, and can be opened by a venting valve 3b, shown in FIG. 1, to establish communication between the inlet passage 3 and the atmosphere. Since the inlet passage 3 is connected to the interior of the container 5, container 5 is also vented when the venting conduit 3a is opened.

The filling apparatus includes a tube 7 which is connected by a tubular valve body 4 to an outlet tube 8. Valve body 4 has a valve portion 4a cooperating with a seat in bottom 1 of vessel 2 so that the inlet passage 3 is open in the positions of FIGS. 1 and 2 can be closed by raising the valve body 4 as illustrated in FIG. 3.

The means by which tubes 7, 8 and valve body 4 are raised, and by which the container 5 is pressed against the sealing means 6 are well known, and for example, disclosed in the U.S. Patent 1,985,767.

Valve means are secured to the lower end of the outlet tube 8. In an embodiment illustrated in FIGS. 1 to 3, a first tube 9 is secured to the lower end of the outlet

tube 8, while a second tube 11 has an upper flange portion 12 slidable along tube 8, and a lower bottom portion 13 formed with an inlet opening 14. The upper part of inlet opening 14 is formed as a valve seat 14a, and the lower end of outlet tube 8 is formed as a valve seat 8a. A spring 15 engages flange 12 and the upper end of tube 9, and urges valve member 11, 12, 13, 14 to the position illustrated in FIG. 1 in which the bottom part 13 abuts the lower annular edge of tube 9 to close the valve chamber in which a movable valve element, shown to be a ball 10, is located.

Ball 10 is of greater specific gravity than the liquid to be filled into container 5, and will normally drop to a position resting on valve seat 14a and closing inlet 14, as shown in FIG. 3. The diameter of the inlet opening 14 is smaller than the diameter of ball 10, and corresponds substantially to the diameter of the outlet tube 8. However, the diameter of valve ball 10 is slightly smaller than the inner diameter of tube 9 so that an annular gap is formed between ball 10 and the inner surface of tube 9, the thickness of the annular gap being of importance for the proper operation of the apparatus.

When ball 10 is in the position of FIG. 3 closing the inlet 14, high pressure in the valve chamber within tube 9 will urge valve member 11, 12, 13 downwardly against the action of spring 15, so that a gap 18 forms between the edge of tube 9 and the bottom portion 13 of the valve member. Consequently, fluid can escape from the valve chamber through gap 18, and pass through openings 16 in the upper part of the outer tube 11.

A filling apparatus illustrated in FIGS. 1 to 3 is operated in combination with a conventional filling machine, not shown, in the following manner:

An empty container or bottle 5 is pressed against the sealing ring 6 in the bottom of the filling vessel 1. Ball 10 rests on valve seat 14a, while spring 15 holds the valve member in the upper position shown in FIG. 1 in which the bottom 13 abuts the annular edge of tube 9 and blocks communication between the valve chamber in tube 9 and the outlets 16. First, the pressure in the interior of the container 5 must be equalized with the pressure of the gas in the gas space above the liquid in vessel 2, which is accomplished by opening a conventional valve 7a, shown in FIG. 1, at the upper end of tube 7 which leads to the gas space in the upper portion of vessel 2. Gas, such as air, or carbonic acid enters through tubes 7 and 8 the valve chamber, and since ball 10 closes the opening 14, the valve member is urged to its lower position shown in FIG. 3, while spring 15 is compressed. Consequently, air under pressure passes from vessel 2, through tubes 7, 8, and 9, gap 18, the annular space between tubes 9 and 11, and finally through the outlet 16 into the interior of the container 5.

When the same pressure prevails in the container 5 as in the valve chamber within tube 9, spring 15 raises valve member 11, 12, 13, 14 to the position shown in FIG. 1 so that communication between the valve chamber and outlets 16 is interrupted.

During the filling of the liquid from vessel 2 into container 5, valve 4a is in the open position shown in FIGS. 1 and 2 so that the liquid can flow through filter 2a and inlet passage 3 into container 5.

The liquid entering container 5 displaces the air, and gas developed by the liquid, which passes through inlet 14, and tubes 9, 8, and 7 into the gas space in the upper part of supply vessel 2. The gas has sufficient pressure to slightly raise ball 10 and the gap between ball 10 and the inner surface of 9 is so dimensioned that ball 10 is only slightly raised to the position shown in FIG. 1, but is not blown to the position in FIG. 2.

Inlet 14 is located at the desired level of the liquid in container 5. When the liquid has reached this level, a gas cushion is formed in the neck portion of the container, and the liquid has the tendency to enter inlet 14, and the valve chamber within tube 9. This accelerates the entry

5 of the last gas and air passing through inlet 14 so that ball 10 is blown to its upper position shown in FIG. 2 in which it is seated on valve seat 8a, and closes the outlet tube 8.

The diameter of ball 10 is selected in such a manner that it performs the above explained function. If the ball 10 were too small, the increased force of the gas flow would not be sufficient to blow the ball to the higher position shown in FIG. 2.

10 Since ball 10 closes outlet tube 8, the liquid cannot rise in outlet tube 8, although a small amount of liquid enters the valve chamber.

15 Since no air or gas can escape from container 5, no additional liquid can enter container 5, so that it is filled to the desired level determined by the position of the inlet 14.

The filling device is now raised to the position shown in FIG. 3 in which valve 4a closes inlet passage 3. Ball 10 drops to the lower position resting on valve seat 14a.

20 A venting valve 3b, shown in FIG. 1, is now opened in venting conduit 3a, so that the interior of container 5 communicates with the atmosphere, and the pressure above the liquid in container 5 drops, and becomes smaller than the pressure in tubes 7, 8, and the valve chamber within tube 9. This pressure is sufficient to move valve member 11, 12, 13 downwards against the action of spring 15 so that gap 18 is formed between the lower end of tube 9 and the bottom portion 13, which permits air under pressure to pass from the valve chamber, through gap 18, the annular space between tubes 9 and 11, and finally through outlet openings 16 into the air space in the upper portion of container 5. The small quantity of liquid which entered the valve chamber during the preceding operation is thus blown out of the valve chamber into the air space in the container. Since the outlet openings 16 are located higher than the level of the liquid, the liquid is not disturbed, and no turbulence and foam is created in the liquid in container 5.

25 Consequently, the pressure relief can be carried out very rapidly, and the liquid can be filled in hot condition without the danger that the liquid is caused to foam and will be discharged when container 5 is separated from sealing means 6.

30 Since the upper space in container 5 is already vented through conduit 3a, container 5 can now be removed, and a new container placed in filling position abutting sealing means 6.

35 The embodiment illustrated in FIGS. 4 to 7 has the same general arrangement as the embodiment of FIGS. 1 to 3, and corresponding parts are indicated by the same reference numerals. The construction of the valve means, however, is different. A tube 9' is secured to the lower end portion of the outlet tube 8, and has a hexagonal outer surface, as best seen in FIG. 7. An outer tube 9" surrounds tube 9', and is secured to the longitudinally extending edges on the outer surface of tube 9' so that longitudinal passages 9a are formed which end at the upper ends of tubes 9' and 9". A valve member in the form of a ring 20 is slidably mounted on tube 8, and normally rests on the upper ends of tubes 9', 9", closing the outlets at the upper ends of passages 9a. The lower edge of tube 9' is permanently spaced from the bottom portion 13' and forms a gap 18' with the same. The inlet 14 communicates with two inlet portions 14b which extend at angles to the longitudinal direction of inlet 14. Valve seat 14a is raised above the upper surface of the bottom portion 13'. The embodiment illustrated in FIGS. 4 to 7 is used in combination with conventional filling apparatus, and operates as follows: An empty container or bottle 5 is pressed against sealing means 6 so that the interior of the container communicates through the inlet passage 3 with the lower portion of vessel 2 in which liquid under pressure is located. Valve ball 10 is seated on seat 14a, and valve 4a is closed as shown in FIG. 6. Consequently, no liquid can enter into container 5, while tubes 7 and 8 communicate

with the air and gas space above the liquid in vessel 2 when a conventional valve, not shown, is opened at the upper end of tube 7.

Gas or air under pressure passes through gap 18' and passages 9a, so that the valve ring 20 is raised to the position shown in FIG. 6, permitting the gas to enter the interior of container 5. When no further gas flows through passages 9a after pressure equalization, valve ring 20 drops to the position shown in FIGS. 4 and 5. The apparatus is now lowered to the position shown in FIG. 4, so that liquid can flow from the lower portion of vessel 2 through inlet passage 3 into the container. The displaced air passes through the inlet 14, 14b and slightly raises ball 10 so that the air can escape through tubes 9', 8 and 7 into the upper portion of vessel 2.

When the liquid has reached its desire level in the region of the inlet 14, 14b, it tends to enter the inlet which causes the last air to rapidly pass through the inlet 14 and valve seat 14a so that the correspondingly dimensioned ball 10 is blown to the higher closing position shown in FIG. 5 abutting valve seat 18a and closing outlet tube 8. Since the air can no longer escape from container 5, no additional liquid flows from vessel 2 into container 5. When the device is raised to the position of FIG. 6, and the inlet passage is closed, ball 10 drops on to valve seat 14a. The venting valve, not shown, in conduit 3a is now opened, so that the interior of container 5 communicates with the atmosphere, and the pressure drops in container 5 below the pressure prevailing in vessel 2, tubes 7, 8, 9', and passages 9a so that the air and gas tend to escape through the outlets at the upper ends of passages 9a and raises valve ring 20 to the position illustrated in FIG. 6 permitting the gas to blow out any liquid, which has entered the valve chamber in tube 9', through the outlets at the upper ends of passages 9a. Since the blown out air and liquid are thrown into the air space above the level of the liquid in container 5, the liquid is not disturbed, and no turbulence or foam develops in the liquid.

Venting conduit 3a effects again a reduction of the pressure in container 5 to atmospheric pressure, so that container 5 can be removed, and replaced by an empty container.

The general arrangement of the embodiment illustrated in FIGS. 8 to 11 corresponds to the above described embodiments, but the valve construction is simplified. A tube 19 is secured to the lower end of outlet tube 8, and has in its upper portion a plurality of openings 19a arranged in a circle in an inner flange portion of tube 19. The lower bottom portion 13 of tube 19 has two oblique inlet portions, and a central inlet 14 terminating in a raised valve seat 14a. The valve ball 10 is located in the valve chamber within tube 19, and is movable between a position resting on valve seat 14a, and a higher position abutting valve seat 8a and closing outlet tube 8.

The embodiment of FIGS. 8 to 11 operates in combination with a conventional filling machine as follows: An empty container 5 is pressed against sealing means 6 while ball 10 rests on valve seat 14a. Valve 4a closes the inlet passage 3 in the position shown in FIG. 10. The conventional valve at the upper end of tube 7 is opened, so that air and gas under pressure enter the valve chamber, and pass through outlet openings 19a into the interior of container 5 while raising valve ring 20, as shown in FIG. 10. When the pressure is equalized, valve ring 20 drops to the position shown in FIG. 8.

The device is now lowered so that valve 4a opens inlet passage 3, and liquid under pressure flows into container 5 which causes the air to escape from container 5 through inlet 14b, 14 whereby ball 10 is slightly raised as shown in FIG. 8. When the level of liquid reaches substantially the level of the inlet 14, the last escaping air moves more rapidly through inlet 14 and valve seat 14a, and blows ball 10 to its upper position closing outlet tube 8. No further air can escape from

container 5, so that the flow of liquid into container 5 is terminated. The device is now raised so that valve 4a closes whereupon ball 10 drops onto valve seat 14a. The venting conduit 3a is now opened, and the pressure in container 5 is thus reduced. The pressure of vessel 2, however, still acts in tubes 7, 8 and in the valve chamber so that some gas escapes through outlets 19a raising valve ring 20 to the position illustrated in FIG. 10, and blowing any liquid which has entered into the valve chamber out of outlets 19a into the air space above the liquid in container 5. In this manner, no turbulence or foaming is caused in the liquid, and container 5 can be removed from the machine without discharging any foam or liquid.

It will be understood that each of the elements described above or two or more together, may also find a useful application in other types of apparatus for filling containers with a liquid under pressure differing from the types described above.

While the invention has been illustrated and described as embodied in a filling device permitting separation of a container from a filling vessel containing liquid under pressure without foaming of the liquid in the container, it is not intended to be limited to the details shown, since various modifications and structural changes may be made without departing in any way from the spirit of the present invention.

Without further analysis the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed and desired to be secured by Letters Patent is:

1. In an apparatus for filling containers with a liquid under pressure, in combination, a tube adapted to project into a container for receiving discharged air; valve means forming a valve chamber having a lower inlet adapted to be located at the desired level of a liquid in the container and a higher outlet, a movable valve element for closing said inlet and said tube, respectively, so that the pressure in said valve chamber is increased when said valve element closes said lower inlet, and a movable valve member having a normal position for blocking passage of air through said outlet and actuated position permitting passage of air through said outlet and being responsive to the pressure in said valve chamber to move to said actuated position when the pressure in said valve chamber is increased whereby air is discharged from said chamber through said outlet into the space above the level of the liquid in the filled container so that foaming of the liquid is prevented.

2. In an apparatus for filling containers with a liquid under pressure, in combination, filling means including an outlet tube having a lower end adapted to project into the container for receiving discharged air from the same; valve means secured to said lower end of said tube communicating with the same and having a lower inlet adapted to be located at the desired level of liquid in the container and a higher outlet for air located above said level, said valve means including a movable valve element movable between an open position permitting air to pass from said container through said inlet and out of said outlet tube, a higher closing position closing said tube to terminate filling, and a lower closing position closing said lower inlet, and a valve member responsive to pressure and operable between a normal position blocking discharge from said higher outlet and an actuated position permitting discharge from said higher outlet, said valve member moving to said actuated position in response to pressure in said valve means when said valve

element is in said lower closing position whereby air is discharged from said outlet into the space above said level of the liquid in the filled container so that foaming of the liquid is prevented.

3. In an apparatus for filling containers with a liquid under pressure, in combination, filling means including inlet control means movable between an open position for connecting the container to a source of liquid under pressure and a closing position disconnecting the source from the container, venting means for venting the container in said closed position, and an outlet tube having a lower end adapted to project into the container for receiving discharged air from the same; valve means secured to said lower end of said tube communicating with the same and having a lower inlet adapted to be located at the desired level of liquid in the container and a higher outlet for air located above said level, said valve means including a movable valve element responsive to flow of air through said inlet to move between an open position permitting air to pass from said container through said inlet and out of said outlet tube, a higher closing position closing said tube to terminate filling, and a lower closing position closing said lower inlet, and a valve member responsive to pressure and operable between a normal position blocking discharge from said higher outlet and an actuated position permitting discharge from said higher outlet, said valve member moving to said actuated position in response to pressure in said valve means when said valve element is in said lower closing position whereby air is discharged from said outlet into the air filled vented spaced above said level of the liquid in the filled container so that foaming of the liquid is prevented.

4. In an apparatus for filling containers with a liquid under pressure, in combination, filling means including an outlet tube having a lower end formed with a first valve seat adapted to project into the container for receiving discharged air from the same; valve means secured to said lower end of said tube communicating with the same and having a lower inlet formed with a second valve seat and adapted to be located at the desired level of liquid in the container and a higher outlet for air located above said level, said valve means including a movable valve ball heavier than the respective liquid and disposed movable between an open position permitting air to pass from said container through said inlet and out of said outlet tube, a higher closing position located on said second valve seat and closing said tube to terminate filling, and a lower closing position located on said first valve seat and closing said lower inlet, and a valve member responsive to pressure and operable between a normal position blocking discharge from said higher outlet and an actuated position permitting discharge from said higher outlet, said valve member moving to said actuated position in response to pressure in said valve means when said valve ball is in said closing position whereby air is discharged from said outlet into the space above said level of the liquid in the filled container so that foaming of the liquid is prevented.

5. In an apparatus for filling containers with a liquid under pressure, in combination, filling means including an outlet tube having a lower end adapted to project into the container for receiving discharged air from the same; valve means including a first tube secured to said lower end of said outlet tube, a second tube having an upper tube portion mounted for movement on said outlet tube and having an outlet, and a lower bottom portion formed with a valve seat and having an inlet communicating with said valve seat and adapted to be located at the desired level of liquid in the container so that said outlet is located above said level, a movable valve ball located in said first tube and being responsive to pressure to move between an open position raised from said valve seat and permitting air to pass through said inlet and out of said outlet tube, a higher closing position closing said outlet

5 tube to terminate filling, and a lower closing position located on said valve seat to close said lower inlet, and spring means urging said second tube to a normal position in which said bottom portion of said second tube abuts the lower end of said first tube to block discharge from said higher outlet, said second tube having an actuated lower position permitting discharge from said higher outlet, and moving to said actuated position in response to pressure in said first tube when said ball is in said lower closing position whereby air is discharged from said outlet into the space above said level of the liquid in the filled container so that foaming of the liquid is prevented.

6. In an apparatus for filling containers with a liquid under pressure, in combination, filling means including an outlet tube having a lower end adapted to project into the container for receiving discharged air from the same; valve means including a first tube secured to said lower end of said outlet tube, a second tube having a lower bottom portion formed with a valve seat and having an inlet communicating with said valve seat and adapted to be located at the desired level of liquid in the container, said second tube being secured to and forming passage means with said first tube, said passage means having an outlet located above said level, a movable valve ball located in said first tube and being responsive to pressure to move between an open position raised from said valve seat and permitting air to pass through said inlet and out of said outlet tube, a higher closing position closing said outlet tube to terminate filling, and a lower closing position located on said valve seat to close said lower inlet, and a valve ring slidable on said outlet tube and having a normal position for blocking discharge from said higher outlet and an actuated higher position permitting discharge from said higher outlet, and moving to said actuated position in response to pressure in said first tube when said ball is in said lower closing position whereby air is discharged from said outlet into the space above said level of the liquid in the filled container so that foaming of the liquid is prevented.

7. An apparatus as set forth in claim 6 wherein said first tube has a polygonal outer surface with longitudinal edges, the inner surface of said second tube abutting said edges, and the sides of said polygonal surface forming said passage means with the inner surface of said second tube.

8. In an apparatus for filling containers with a liquid under pressure, in combination, filling means including an outlet tube having a lower end adapted to project into the container for receiving discharged air from the same; valve means including a valve member having a tubular upper part secured to said outlet tube and formed with an outlet and a lower part formed with a valve seat and with an inlet communicating with said valve seat and adapted to be located at the desired level of a liquid in the container so that said outlet is located above said level, a movable ball located in said tubular part and being responsive to pressure to move between an open position raised from said valve seat and permitting air to pass through said inlet and out of said outlet tube, a higher closing position closing said outlet tube to terminate filling of the container and a lower closing position located on said valve seat to close said lower inlet, and a valve ring slidable on said outlet tube and having a normal position for blocking discharge from said higher outlet and an actuated higher position permitting discharge from said higher outlet, said valve ring moving to said actuated position in response to pressure in said valve member when said valve ball is in said lower closing position whereby air is discharged from said outlet into the space above said level of the liquid in the filled container so that foaming of the liquid is prevented.

9. An apparatus as set forth in claim 8 wherein said upper part of said valve member is an inner flange se-

cured to said outlet tube and formed with a plurality of openings arranged in a circle surrounding said outlet tube and constituting said outlet.

10. An apparatus as set forth in claim 8 wherein said lower part of said valve member has a downwardly tapering bottom face and wherein said inlet has a central inlet portion terminating in said valve seat and two downwardly inclined inlet portions opening on opposite sides of said bottom face.

11. In an apparatus for filling containers with a liquid under pressure, in combination, a tube adapted to project into a container for receiving discharged air; valve means forming a valve chamber having a lower inlet adapted to be located at the desired level of a liquid in the container and a higher outlet, a movable valve element for closing said inlet and said tube, respectively, so that the pressure in said valve chamber is increased when said valve element closes said lower inlet, and a movable gravity operated valve member having a normal lower position covering said outlet for blocking passage of air through said outlet and actuated raised position permitting passage of air through said outlet and being raised by air passing through said outlet to move to said actuated position when the pressure in said valve chamber is increased whereby air is discharged from said chamber through said

10 25 2,794,453

outlet into the space above the level of the liquid in the filled container so that foaming of the liquid is prevented.

12. In an apparatus for filling containers with a liquid under pressure, in combination, a tube adapted to project 5 into a container for receiving discharged air; valve means forming a valve chamber having a lower inlet adapted to be located at the desired level of a liquid in the container and a higher outlet, a movable valve element for closing said inlet and said tube, respectively, so that the pressure in said valve chamber is increased when said valve element closes said lower inlet, and a movable spring-loaded valve member having a normal higher position for blocking passage of air through said outlet and an actuated lower position permitting passage of air through said outlet and being responsive to the pressure in said valve chamber to move to said actuated position when the pressure in said valve chamber is increased whereby air is discharged from said chamber through said outlet into the space above the level of the liquid in the filled container so 15 20 that foaming of the liquid is prevented.
